UNITED STATES PATENT OFFICE

152,416

DESIGN FOR A PHONOGRAPH TONE ARM OR THE LIKE

Joseph B. Federico, New Baltimore, Mich., assignor to The Astatic Corporation, Conneaut, Ohio, a corporation of Ohio

Application August 29, 1947, Serial No. 141,125

Term of patent 7 years

(Cl. D26—14)

To all whom it may concern:

Be it known that I, Joseph B. Federico, a citizen of the United States, residing at New Baltimore, in the county of Macomb and State of Michigan, have invented a new, original, and ornamental Design for Phonograph Tone Arm or the like, of which the following is a specification, reference being had to the accompanying drawing, forming part thereof.

Figure 1 is a perspective view of a phonograph tone arm or the like embodying my novel design.

Figures 2, 3 and 4 are sections taken at lines II—II, III—III, and IV—IV, respectively, of Figure 1; and

Figure 5 is a side elevation of the rearward end portion of the phonograph tone arm of Figure 1.

I claim:

The ornamental design for a phonograph tone arm or the like, as shown.

JOSEPH B. FEDERICO.
